LOCK MECHANISM

Nickolas Schmitt, Wolverine, Mich.

Application January 14, 1952, Serial No. 266,289

10 Claims. (Cl. 70—150)

1

The present invention relates to a lock mechanism which is adapted for use with doors of refrigerators, airplanes, automobiles, and the like. This is a continuation-in-part of my co-pending application, Serial No. 229,999, filed June 5, 1951.

It is among the objects of the present invention to provide a lock mechanism for a door which will be noiseless at all times when the door is either opened or closed and which is constructed and arranged to compensate for wear of its working parts to prevent rattling, vibrating or the like thereof after it has been in use.

It is another object of the present invention to provide a lock mechanism of the foregoing character which can be opened by pushing against the push button and simultaneously pulling on the door, and which is constructed and arranged to remain closed in the event the door is not pulled simultaneously with the pushing action on the push button, thereby preventing accidental opening of the door if the push button is inadvertently depressed, said lock being further characterized in that it is constructed and arranged to have primary and secondary holding means so that the latter will prevent opening of the door or the like in which the lock is installed in the event the former does not properly hold the lock closed.

It is still another object of the present invention to provide a lock mechanism of the foregoing character in which the lock mechanism will compensate for any misalignment of the door with respect to the door frame, and which has relatively few parts which can be economically produced.

Other objects of this invention will appear in the following description and appended claims, reference being had to the accompanying drawings forming a part of this specification wherein like reference characters designate corresponding parts in the several views.

In the drawings:

Fig. 1 is an elevation, partly in section, showing the internal structure of the lock forming a part of the present invention;

Fig. 2 is a fragmentary view drawn to a reduced scale showing the present lock mounted in place on the doors of a motor vehicle;

Fig. 3 is a fragmentary sectional view taken on line 3—3 of Fig. 2;

Fig. 4 is a view similar to that of Fig. 3 and illustrates a modified construction by which control of the lock may be had by remote means;

Fig. 5 shows another modification of the invention whereby the door of the motor vehicle can be locked with a key; and

2

Fig. 6 is a fragmentary elevation drawn to reduced scale wherein the lock is shown mounted in position for locking the hood for a motor vehicle.

5 Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

15 The lock shown in Fig. 1 of the drawings and disclosed hereinafter is very similar to the lock disclosed in my aforesaid co-pending application. The distinctions which occur between the present lock and the lock in my prior application will be 20 described hereinafter and reference is hereby made to the aforesaid application for a more complete description of the lock construction.

25 Referring now to the drawings, and particularly to Fig. 1 thereof, the structure forming the lock can be seen. A housing 10 is provided in which are pivotally mounted at 12 a pair of dogs 14 and 16 which are adapted when in their closed positions to grip the transverse pin 18 which is an integral part of the frame member 20. As 30 can be seen, the dogs 14 and 16 each have a pair of slots 22 and 24 cut in their adjacent edges for holding pin 18. The slots 22 hold the pins when the lock is fully closed, and slots 24 act as a safety catch so that in the event a door or the like in which the lock is mounted is not properly closed, the safety catch will prevent the door from accidentally opening.

35 The dogs 14 and 16 are maintained in their closed position, as shown in Fig. 1, by the action of the leaf spring 26 which is secured to the side of the housing 10, as at 28. However, it should be understood that any other spring means may be employed which will bias the dogs 14 and 16 to a closed position.

40 The dogs 14 and 16 can be opened to release the pin 18 by the action of the push button 30 which includes the rod 32 with the V-shaped cap 34 on its inner end and the coil spring 36 for biasing the push button 30 away from housing 10. It is to be understood, however, that other means such as a crank or the like may be used for spreading the dogs 14 and 16, and the present invention is not limited merely to a push button of the type disclosed in this application.

45 As can be seen, the dogs 14 and 16 have extensions 38 and 36, respectively, on their inner ends which are in position to be engaged and spread

apart by the V-shaped cap 34 when the push button 30 is depressed. This in turn will cause pivotal movement of the dogs about the pin 12, thereby opening the dogs 14 and 16.

In order to prevent the lock from rattling or otherwise becoming noisy, as may be the case when it becomes worn and old, the dogs 14 and 16 are designed so that they will never have any clearance between their inner surfaces and the pin 18. This is effected by making the inner curvatures 48 and 42 concentric near their open ends concentric with that of the pin 12. Near the closed ends, the curvatures 48 and 42 converge toward the axis of pin 12. Thus, when the curvatures 48 and 42 become worn, the spring 26 will press the dogs 14 and 16 further closed to a position where the curvatures 48 and 42 again are snug with the pin 18.

One of the important features of the present invention which was broadly disclosed in the aforesaid application are the means provided to prevent spreading of the dogs 14 and 16. As seen in Fig. 1, a plunger 44 extends into the housing 10 and abuts the edges of the dogs 14 and 16 so that the latter are not free to pivot and therefore are in a locked position, preventing them from being opened to release the pin 18. In order to open the dogs 14 and 16, it is only necessary that the pin 44 be withdrawn from the path of pivotal movement of said dogs. Preferably this pin will be withdrawn axially as is disclosed in the several embodiments of the present invention.

Figs. 2 and 3 show an embodiment of the present invention mounted in the doors of a conventional automobile. As there shown, the push buttons 30 are the only portion of the locks which extend outwardly from the body of said automobile and they are located below the door handles 50 so that the doors of the automobile can be readily opened merely by depressing the push buttons and simultaneously pulling on the door handles.

In this embodiment, the pin 18A is mounted in a fixed position in the center post 52 of the automobile, and the lock is mounted in the door behind the flange 54 which overlaps the center post 52. As is believed readily understood, when the push button 30 is depressed, the V-shaped cap 34 will cause pivotal movement of the dogs 14 and 16 about the pin 12 so that the dogs 14 and 16 release the pin 18A to permit opening of the door 56. When the door 56 is swung closed, the ends of dogs 14 and 16 will first contact pin 18A, and by virtue of their curved edges, will be spread apart against the biasing action of spring 26 to permit the slots 22 to overlap pin 18A and thereby hold the door 56 in a closed position. One of the desirable features of this modification is that the lock does not require oil or grease, and, therefore, will always be clean. Thus, clothing or the like will not be soiled by contacting the same.

There are other various constructions and arrangements that may be utilized for locking the dogs 14 and 16 in a closed position. A manually operated plunger, such as is indicated by the reference number 44 in Fig. 1 may be used. An embodiment of the invention by which the dogs 14 and 16 may be remotely locked in place is shown in Fig. 4. Here the plunger 44B is remotely controlled by means of a solenoid 60 which is operated by a conventional electric circuit, not shown. If desired, this circuit can be located so that the driver of the motor vehicle can lock the doors by actuating a switch located on the instrument panel. Likewise, such an arrange-

ment is very suitable when the present invention is used in airplanes or the like, where it is desired to control by remote means the opening and closing of the doors.

5 Referring next to Fig. 5, an embodiment of the present invention is shown wherein the dogs 14 and 16 can be locked in place by means of a conventional automobile door lock 62. In this embodiment, a crank 64 is caused to rotate by turning a key in the lock 62. This, in turn, causes axial movement of plunger 44C which is connected to crank 64 by the pins 66, thereby selectively locking or releasing the dogs 14 and 16.

The present lock mechanism may also be very advantageously used for holding down the hood of a motor vehicle. This arrangement can be seen in Fig. 6, wherein the hood of motor vehicle 72 is held in a closed position by the lock shown at 74. The latter may be connected in any suitable manner by a support bracket or the like (not shown) which is joined to a stationary portion of the vehicle. The pin 18D is joined to the hood by the flange 76 and is adapted to be held by the dogs 14 and 16.

15 Located on the instrument panel 88 of the motor vehicle is a handle 82 to which is attached the cable 84. The latter is joined to one arm of the bell crank 86 which is pivotally mounted at 88. The other arm of the bell crank abuts the push button 30. Thus a remote operating means for the push button 30 is provided by which the operator can cause the dogs 14 and 16 to release the pin 18D merely by drawing on the handle 82.

20 A conventional compression spring 90 is provided so that when the operator causes the dogs 14 and 16 to release pin 18D, the spring 90 will bias the hood upwardly away from dogs 14 and 16. Any suitable manually operated safety catch mechanism (not shown) such as is now conventional on motor vehicles, may be employed, if desired, to hold the hood 76 in a partially closed position. As is well known, such safety catch mechanisms are adapted to be manually opened to permit the hood to be swung to a fully opened position, and thus, the hood will not accidentally swing open while the motor vehicle is in motion.

25 From the foregoing it is to be seen that many applications can be made of the present locking mechanism. It can be opened by direct or remote operating means, and similarly, the dogs 14 and 16 thereof can be locked either by direct or remote means. Further, the dogs can be so constructed and arranged as to have primary and secondary holding means to prevent a car door or the like from accidentally opening.

30 Having thus described my invention, I claim:
1. A lock device comprising a lock having a pair of pivotally mounted dogs adapted when closed to hold a pin, spring means for urging said dogs to a closed position and a push button for spreading said dogs to release said pin, and a means extending from a remote position into said lock and abutting against said dogs to prevent the latter from swinging to an open position, said means being operable from the remote position to be withdrawn, for releasing said dogs so that the same can be opened.

35 2. A latch device comprising a lock including a frame structure with a transverse slot extending into one end thereof for receiving a pin, a pair of oppositely disposed dogs pivotally mounted in said frame structure and adapted to hold said pin, a push rod mounted on the other end of said housing and having its one end extending into said frame structure, and projections ex-

tending from said dogs to opposite sides of said one end of the push rod and adapted to be spread apart by the latter to open said dogs and release said pin, and a mechanism extending from a remote position into said latch to prevent said dogs from being opened, said mechanism including a plunger extending into said frame structure and engaging at least one of said dogs to prevent the same from being pivoted to an open position, and means operable from said remote position to move said plunger out of the path of pivotal movement of said dogs so that the latter can be opened.

3. A locking device as claimed in claim 2 wherein said means to move the plunger comprises a solenoid enclosing one end of said plunger.

4. A locking device as claimed in claim 2 wherein said means to move the plunger comprises a key-operated lock adapted to move said plunger upon rotation of the key in the lock.

5. A latch device comprising a lock including a frame structure with a transverse slot extending into one end thereof for receiving a pin, a pair of oppositely disposed dogs pivotally mounted in said frame structure to grip said pin, a push rod mounted on the other end of said housing and having its one end extending into said housing, and projections extending from said dogs to opposite sides of said one end of the push rod and adapted to be spread apart by the latter to open said dogs and release said pin, and a mechanism extending from a remote position into said latch to prevent said dogs from being opened, said mechanism including a plunger slidably mounted in said frame structure for axial movement so that when the plunger is moved in one direction it will abut at least one of said dogs to prevent opening thereof.

6. A latch device comprising a lock including a frame structure with a transverse slot extending into one end thereof for receiving a pin, a pair of oppositely disposed dogs pivotally mounted in said frame structure to grip said pin, a push rod mounted on the other end of said frame structure and having its one end extending into said frame structure and projections extending from said dogs to opposite sides of said one end of the push rod and adapted to be spread apart by the latter to open said dogs and release said pin, and a remote operating means for depressing said push rod so as to open the dogs of said lock.

7. A lock device as claimed in claim 6 wherein said remote operating means comprises a bell crank having its one arm engaging the end of said push rod so as to move the latter when said arm is pivoted, and the other arm having a cable attached thereto for pivoting said bell crank.

8. A latch adapted to engage a pin comprising a frame structure having a slot formed in one end for receiving the pin, a transverse shaft mounted in said frame structure inward of said slot, a pair of oppositely disposed dogs pivotally mounted on said shaft for holding said pin, the holding surface of each of said dogs adjacent the distal ends of the latter being substantially

concentric with the axis of said shaft with the remainder of the holding surface of each dog gradually converging toward said axis so that when said dogs are being fully closed they will draw said pin toward their pivotal mounting, a spring actuated push rod mounted in the other end of said frame structure and having its one end extending toward said transverse shaft, projections extending from said dogs to opposite sides of said one end of the push rod and adapted to be spread apart when the latter is moved against the action of its spring to open said dogs, said dogs each having at least two notches for holding the pin so that the outermost pair can act as a safety catch.

9. A latch adapted to engage a pin comprising a frame structure having a slot formed in one end for receiving the pin, a transverse shaft mounted in said frame structure inward of said slot, a pair of oppositely disposed dogs pivotally mounted on said shaft for holding said pin, the holding surface of each of said dogs adjacent the distal ends of the latter being substantially concentric with the axis of said shaft with the remainder of the holding surface of each dog gradually converging toward said axis so that when said dogs are being fully closed they will draw said pin toward their pivotal mounting, actuating means extending from said frame structure and associated with said dogs for separating the holding surfaces of said dogs, means for urging said dogs to a closed position, and said dogs each having at least two notches for holding the pin so that the outermost pair can act as a safety catch.

10. A latch adapted to engage a pin comprising a frame structure having a slot formed in one end for receiving the pin, a transverse shaft mounted in said frame structure inward of said slot, a pair of oppositely disposed dogs pivotally mounted on said shaft for holding said pin, the holding surface of each of said dogs adjacent the distal ends of the latter being substantially concentric with the axis of said shaft with the remainder of the holding surface of each dog gradually converging toward said axis so that when said dogs are being fully closed they will draw said pin toward their pivotal mounting, actuating means extending from said frame structure and associated with said dogs for separating the holding surfaces of said dogs, and means for urging said dogs together.
